DESIGN FOR A DIFFUSER FOR ELECTRIC LIGHTING FIXTURES

Duane L. Ripley, Buffalo, N. Y., assignor to
Markel Electric Products, Inc., Buffalo, N. Y., a
corporation of New York

Application October 29, 1936, Serial No. 65,562

Term of patent 3½ years

To all whom it may concern:

Be it known that I, Duane L. Ripley, a citizen of the United States, residing at Buffalo, in the county of Erie and State of New York, have invented a new, original, and ornamental Design for a Diffuser for Electric Lighting Fixtures, of which the following is a specification, reference being had to the accompanying drawing forming a part thereof.

In said drawing:

Figure 1 is a top view of a diffuser for electric lighting fixtures embodying my new design.

Figure 2 is a side view of the diffuser.

Figure 3 is a bottom view thereof.

I claim:

The ornamental design for a diffuser for electric lighting fixtures substantially as shown.

DUANE L. RIPLEY.
